US00D845978S

(12) **United States Design Patent** (10) **Patent No.:** **US D845,978 S**
Gorskiy (45) **Date of Patent:** **** Apr. 16, 2019**

(54) **DISPLAY SCREEN WITH GRAPHICAL USER INTERFACE**(71) Applicant: **YANDEX EUROPE AG**, Lucerne (CH)(72) Inventor: **Konstantin Pavlovitch Gorskiy**, Moscow (RU)(73) Assignee: **YANDEX EUROPE AG**, Lucerne (CH)(***) Term: **15 Years**(21) Appl. No.: **29/600,365**(22) Filed: **Apr. 12, 2017****Related U.S. Application Data**

(62) Division of application No. 29/443,838, filed on Jan. 23, 2013, now abandoned.

(51) **LOC (11) Cl.** **14-04**(52) **U.S. Cl.**USPC ..... **D14/486**(58) **Field of Classification Search**USPC D14/485-495; 715/700, 702, 716, 719, 715/726, 733, 763, 765, 781, 783, 864
